UNITED STATES PATENT OFFICE.

JOSEPH AMENDT, OF BLAIRSVILLE, PENNSYLVANIA.

CURTAIN-POLE.

No. 806,513.

Specification of Letters Patent.

Patented Dec. 5, 1905.

Application filed October 11, 1904. Serial No. 227,999.

To all whom it may concern:

Be it known that I, JOSEPH AMENDT, a citizen of the United States of America, residing at Blairsville, in the county of Indiana and State of Pennsylvania, have invented certain new and useful Improvements in Curtain-Poles, of which the following is a specification, reference being had therein to the accompanying drawings.

10 This invention relates to certain new and useful improvements in curtain-poles, and has for its object to dispense with curtain rings, hooks, and the like which have heretofore been commonly used for attaching one or more 15 curtains to a pole.

Another object of this invention is to provide novel means whereby one or more curtains may be easily and quickly attached to a curtain-pole, whereby the curtains may be removed when desired and may be draped to conform to any desired configuration.

Briefly described, my improved curtain-pole is preferably constructed of wood and is similar in all respects to the curtain-poles 25 commonly used, with the exception that longitudinally of its length it is provided with a groove, and in this groove is adapted to fit a rod which carries upon each of its ends a metallic disk or plate having a central aperture 30 formed therein. The curtain is adapted to be placed in the groove and held therein by the rod, which is held within said groove by screws engaging in the ends of the curtain-pole.

35 The above construction will be hereinafter more fully described and then specifically pointed out in the claims, and, referring to the drawings accompanying this application, like numerals of reference designate corresponding 40 parts throughout the several views, in which—

Figure 1 is a side elevation of my improved curtain-pole. Fig. 2 is a longitudinal sectional view of the same. Fig. 3 is a perspective view of the detachable member of my improved pole, and Fig. 4 is a perspective view of the pole proper.

To put my invention into practice, I employ a pole 1 of the ordinary type, which is 50 commonly constructed of wood, and longitudinally of the length of said pole I form a groove 2. The ends of the pole are provided

with apertures 3 3, in which the screws 4 4, carrying ornamentations 5 5, are secured. In conjunction with the pole just described I 55 employ a detachable member which consists of a rod 6, this rod being of such a size as to fit within the groove 2 in the curtain-pole, and upon each end of the rod I secure the metallic disks or plates 7, these disks being arranged 60 tangentially to the rod 6, and centrally of each disk is formed an aperture 8.

The reference-numerals 9 9 designate curtains which are adapted to be secured in the curtain-pole, and the upper edges of the curtains are adapted to be placed in the groove 2 and the rod 6 placed therein to impinge the curtains against the curtain-pole, and prior to securing the screws 4 4 in the ends of the pole the disks or plates 7 are engaged 70 with the end of the pole, and the screws pass through the apertures 8 of the disks into the apertures 3 of the pole. Any desired ornamentation may be carried by the screws 4, whereby the general appearance of the curtain-pole will be enhanced, and it will be observed by the fastening means within the pole that said curtains may be arranged or draped to conform to any desired configuration. 75

80 While I have herein shown the preferred manner of constructing my improved curtain-pole, it will be noted that various changes may be made in the details of construction without departing from the general spirit and 85 scope of the invention.

What I claim as new, and desire to secure by Letters Patent, is—

1. A curtain-pole having a groove formed therein, a rod adapted to fit within said groove, 90 plates carried by said rod and extending at right angles to the rod and over the ends of the pole, and means for securing said rod within said groove, substantially as described.

2. The combination with a curtain, of a 95 pole, said pole having a groove formed longitudinally therein, a rod adapted to fit within said groove to retain said curtain therein, plates carried by said rod, and ornamentations carrying screws, said screws passing through 100 said plates and into the pole for securing said plates to the ends of said pole.

3. A curtain-pole comprising a body portion having a groove formed longitudinally

therein, the ends of said pole having openings formed therein, a rod, integral plates carried by said rod, said plates extending over the ends of the pole and having openings formed therein, and screws passing through said plates for securing said rod and said plates to said curtain-pole.

In testimony whereof I affix my signature in the presence of two witnesses.

JOSEPH AMENDT.
